UNITED STATES PATENT OFFICE.

ALBERT J. BORK, OF BUFFALO, NEW YORK, ASSIGNOR OF ONE-HALF TO
CHARLES HULL, OF SAME PLACE.

DESIGN FOR A BANNER.

SPECIFICATION forming part of Design No. 32,055, dated January 2, 1900.

Application filed November 13, 1899. Serial No. 736,879. Term of patent 31 years.

To all whom it may concern:

Be it known that I, ALBERT J. BORK, a citizen of the United States, residing at No. 196 Grape street, Buffalo, in the county of Erie and State of New York, have invented certain new and useful Improvements in a Design for a Banner, of which the following is a specification.

This invention relates to a design for banners; and it consists in the novel arrangement and artistic details, all of which will be readily seen by reference to the accompanying drawing, in which the figure represents a plan view of my invention.

Referring to the drawing by reference-numerals, 1 indicates a substantially rectangular field, longitudinally of which are arranged a series of equidistant parallel lines 2, forming alternating red and white stripes 3 and 4, respectively. Centrally the rectangular field is a circular field 5, divided by the intersecting lines 6 and 7 to represent the imaginary lines of latitude and longitude of the Western Hemisphere, while in the upper left-hand corner of the field 1 is a third field

8 of blue, on which are arranged a series of stars 9.

The continents of North and South America (indicated by the numerals 10 and 11) are positioned on the field 5 in correct geographical location with relation to the lines of latitude and longitude, and the possessions of each country contained in the Western Hemisphere are covered by the flag of the country under whose sovereignty it is. Thus Alaska 35 and the United States are covered by the "Stars and Stripes," while Canada will be covered by the flag of England, each country being covered by the colors of its standard.

Having thus described my invention, what 40 I claim, and desire to secure by Letters Patent, is—

The design for a banner as herein shown and described.

In testimony whereof I affix my signature 45 in presence of two witnesses.

ALBERT J. BORK.
